ELECTRICALLY-OPERATED TOOTHBRUSH
Marcel Alexis Frésard, Geneva, Switzerland, assignor to
Etablissement Aesup, Vaduz, Liechtenstein, a firm of
LiechtensteinFiled Nov. 14, 1961, Ser. No. 152,345
Claims priority, application Switzerland Nov. 21, 1960
6 Claims. (Cl. 15—22)

This invention relates to electrically-operated toothbrushes, and particularly to a hygienic watertight arrangement therefor.

Electrically-operated toothbrushes are now known including a casing forming a handle, a shaft extending through the front end of the casing for carrying a toothbrush head, and electrical means mounted within the casing for oscillating the shaft.

One particular type is disclosed in U.S. Patent 2,917,758, issued December 22, 1959, to Held et al. In this toothbrush the shaft is rotationally oscillated so as to impart a corresponding motion to a toothbrush head attached thereto and brush the teeth in the lengthwise direction thereof. Other types are known in which a longitudinal oscillation is imparted to the shaft.

In an electrically-operated toothbrush, it is important to prevent the entry of water or other liquid into the portion of the casing containing the electrical driving means, both because of the corrosive effects of the water and the danger of electric shock. Watertightness is particularly important when the toothbrush is energized from the power mains where the line voltage can be dangerous.

With an oscillating shaft it is difficult to achieve watertightness, while at the same time permitting oscillations of sufficient amplitude to be obtained with the limited power available. Thus, a watertight bearing between the shaft and the front end of the casing has been found insufficient to maintain watertightness over an extended period of use.

To further assure watertightness it has been found desirable to employ a flexible water-impermeable partition member extending between the shaft and the casing, and secured to the shaft and casing in watertight relationship. Due to the flexibility of the partition member, it may be deformed during operation and oscillations are not unduly impaired. In particular, with the rotationally oscillating brush of the aforesaid patent, it has been found advantageous to employ a sleeve of flexible water-impermeable material which encircles the shaft and extends therealong a substantial distance. The sleeve is flared, with its smaller diameter front end (toward the end of the casing where the shaft protrudes) secured tightly around the shaft, and its larger diameter rear end secured in watertight relationship with the inside of the casing.

U.S. Patent No. 3,060,474, issued October 30, 1962, to Woog discloses an arrangement of this type.

It is desirable to have the flexible partition member mounted inside the casing to afford protection against accidental damage. However, even with a reasonably watertight bearing between the shaft and the front end of the casing it has been found that water, toothpaste, saliva, etc. commonly present during normal use penetrate into the front end of the casing. The elastic partition or sleeve prevents the water mixture from reaching the elec-

2

trical elements. However, bacterial action, etc, is likely to develop, resulting in an unhygienic and musty condition.

In accordance with the present invention, the flexible partition member or sleeve is employed to prevent entry of water, etc. into the electrical portion of the casing, and is mounted inside the casing at the front end thereof so that it cannot easily be damaged, as above described. Then, apertures are provided in the front end of the casing to enable washing of the interior thereof.

Advantageously apertures are formed in the side wall of the front portion of the casing, and preferably on opposite sides of the shaft, together with one or more apertures at the front end of the casing adjacent the shaft. This permits a stream of water to flow through the chamber between the front end of the casing and the partition member, so as to wash out any accumulation of toothpaste, etc. In the specific embodiment described hereinafter, a plurality of apertures are employed adjacent the shaft, and the portions of the casing between the apertures form bearing surfaces which limit lateral displacement of the shaft.

The invention will be more fully understood from the following description of specific embodiments thereof, taken in conjunction with the drawings, in which:

FIG. 1 is an overall view of the toothbrush including handle and attached stem-brush;

FIG. 2 shows a portion of the handle partly in cross-section;

FIG. 3 is a view of the handle from the front end thereof; and

FIG. 4 illustrates a modification.

Referring to FIG. 1, a casing 10 forms a handle, and shaft 11 projects from the front end thereof. In this embodiment the brush head is detachable from the handle, and comprises a stem 12 with bristles 13 mounted thereon, with a coupling at 14 enabling the brush-stem to be conveniently attached and removed. The coupling may be of the type described in application Serial No. 103,482, filed April 17, 1961, by Moret, for "Toothbrush Attachment."

Inside casing 10 is electrical means for oscillating shaft 11, generally indicated by dotted box 15, and in this particular embodiment is a motor of the type shown in the aforesaid Patent 2,917,758. Resilient areas 16, 16' are provided for actuating an internal switch or other mechanism for controlling oscillation of the shaft. Details of these components are not shown since they form no part of the present invention.

Referring to FIG. 2, a sleeve 21 of flexible, water-impermeable material such as neoprene is secured at its front end 22 to an enlarged section 11' of shaft 11. The unstretched diameter of front end 22 may be made smaller than the diameter of shaft portion 11' so that its elasticity produces a tight fit and insures watertightness. The portion 11" of the shaft may be somewhat larger so as to provide an abutment for end 22 of the sleeve. Additional means for insuring a watertight connection may be employed if desired.

The rearward end 23 of sleeve 21 is held tightly against the inside of casing 10 by a ring 24. Thus, the sleeve 21 prevents any entry of water to the rearward portion of the casing 10 where the motor and any electric circuit components are located. In operation the front end 22 twists with respect to rear end 23, the flexibility of the

sleeve allowing this action to take place without impairing the watertight connections with shaft and casing.

The rearward portion of the casing is constructed so as to be watertight. To this end casing 10 is advantageously made in one piece with resilient areas 16, 16' either integral with the casing or firmly adhered thereto. An insulating plastic is preferred for the casing material. In order to permit assembly, a cap 10' of the casing is formed separately and then made integral with the main body of the casing, as by fusing. Electric power is supplied to the toothbrush through conductors 25 and a molded plastic section 26 is provided to insure watertightness at the point where conductors 25 enter casing 10.

A plurality of small apertures 31 are provided in the sidewall of the front portion of the casing, and a like plurality of apertures are formed in the side wall on the opposite side of the shaft, as indicated at 31' in FIG. 2. Also, in order to allow free flow of water through the front section of the casing, a plurality of apertures 33 are provided in the front end of the casing, as shown in FIG. 3. These are adjacent the shaft, and the portions 34 of the casing between the apertures 33 closely approach the shaft and form bearing surfaces which limit lateral displacement of the shaft.

It will be seen that with the apertures arranged as shown, the front portion of the casing can be put into water, or passed under a water tap, in order to wash out any accumulation of toothpaste, etc. Further, when the toothbrush is not in use, the apertures allow air to enter to promote hygienic conditions.

Sleeve 21 may be circumferentially pleated as shown in FIG. 2, or unpleated, or longitudinally pleated, in order to secure adequate flexibility so as not to substantially impair oscillation of shaft 11.

FIG. 4 shows a modification employing an unpleated sleeve 35 which extends somewhat farther along the shaft. The front end 36 is secured to shaft section 11' as described before, and the rear end 37 is tightly pressed against the inside of casing 10" by a ring 24. In this case apertures 38 are placed somewhat farther from the front end of the casing, but still lie between the front end and the region at which the flexible member is secured to the casing. Similar apertures may be formed on the other side of the casing, and in the end of the casing adjacent the shaft, as described in connection with FIG. 2.

I claim:

1. An electrically-operated toothbrush which comprises
  - (a) an elongated casing forming a handle,
  - (b) a shaft extending through the front end of the casing for carrying a toothbrush head,
  - (c) electrical means mounted within the casing for oscillating the shaft,
  - (d) a flexible water-impermeable partition member inside the casing extending between the shaft and the casing and secured to the shaft and casing in watertight relationship,
  - (e) the flexible partition member being secured to the inside of the casing at a region spaced from the front end of the casing,
  - (f) the portion of the casing rearward of the flexible partition member being watertight and said electrical means being mounted therein,
  - (g) at least one aperture in the sidewall of the front portion of the casing ahead of the flexible partition member and at least one aperture in the front end of the casing adjacent the shaft for enabling washing of the interior of the front portion of the casing up to the flexible member by a flow of water therethrough.

2. An electrically-operated toothbrush in accordance with claim 1 including a plurality of apertures in the front end of the casing adjacent the shaft, the portions of the casing between the apertures forming bearing surfaces limiting lateral displacement of the shaft.

3. An electrically-operated toothbrush comprising

- (a) an elongated casing forming a handle,
- (b) an electric motor mounted within the handle,
- (c) a shaft oscillated by the motor and extending through the front end of the casing for oscillating a toothbrush head attached thereto,
- (d) a flexible sleeve of water-impermeable material encircling the shaft inside the casing and having one end secured tightly around the shaft and the other end secured in watertight relationship with the inside of the casing at a region spaced from said front end of the casing for preventing entry of water to the portion of the casing rearward of the sleeve while allowing oscillation of the shaft,
- (e) the portion of the casing rearward of the sleeve being watertight and said electric motor being mounted therein,
- (f) at least one aperture in the sidewall of the casing between the front end of the casing and the region at which the flexible sleeve is secured to the casing and at least one aperture in the front end of the casing adjacent the shaft for enabling washing of the interior of the front portion of the casing up to the flexible member by a flow of water therethrough.

4. An electrically-operated toothbrush in accordance with claim 3 in which the front end of the casing closely approaches the shaft, and including

- (a) a plurality of apertures in the sidewall of the front portion of the casing ahead of the flexible sleeve and on opposite sides of the shaft,
- (b) and a plurality of apertures in the front end of the casing adjacent the shaft,
- (c) the portions of the front end of the casing between the corresponding apertures forming bearing surfaces limiting lateral displacement of the shaft.

5. An electrically-operated toothbrush comprising:

- (a) an elongated casing forming a handle,
- (b) an electric motor mounted within the handle,
- (c) a shaft rotationally oscillated by the motor and extending through the front end of the casing for rotationally oscillating a toothbrush head attached thereto,
- (d) the front end of the casing closely approaching the shaft,
- (e) a flexible sleeve of water-impermeable material encircling the shaft inside the casing and extending therealong a substantial distance,
- (f) the front end of the sleeve being secured tightly around the shaft and the rear end thereof being secured in watertight relationship with the inside of the casing to prevent entry of water to the portion of the casing rearward of the sleeve while allowing rotational oscillation of the shaft,
- (g) the portion of the casing rearward of the sleeve being watertight and said electric motor being mounted therein,
- (h) a plurality of apertures in the sidewall of the front portion of the casing ahead of the flexible sleeve and on opposite sides of the shaft and a plurality of apertures in the front end of the casing adjacent the shaft for enabling washing of the interior of the front portion of the casing up to the flexible sleeve by a flow of water therethrough,
- (i) the portions of the front end of the casing between the corresponding apertures forming bearing surfaces limiting lateral displacement of the shaft.

6. An electrically-operated toothbrush which comprises

- (a) an elongated casing forming a handle,
- (b) a shaft extending from the interior of the casing at the front end thereof for carrying a toothbrush head,
- (c) electrical means mounted within the casing for oscillating the shaft,
- (d) a flexible water-impermeable partition member inside the casing extending between the shaft and the casing and engaging the shaft and casing in substantially watertight relationship,

- (e) the flexible partition member engaging the inside of the casing at a region spaced from the front end of the casing,
  - (f) said electrical means being mounted in the casing rearward of said flexible partition member,
  - (g) at least one aperture in the side wall of the front portion of the casing ahead of the flexible partition member and at least one aperture in the front end of the casing adjacent the shaft for enabling washing of the interior of the front portion of the casing up to the flexible member by a flow of water therethrough.
